UNITED STATES PATENT OFFICE.

JOSEPH MITCHELL CHANDLER, OF EAST BRIDGEWATER, MASSACHUSETTS, ASSIGNOR
TO CLARENCE A. CHANDLER, DOING BUSINESS AS CHANDLER CONSTRUCTION COM-
PANY, OF EAST BRIDGEWATER, MASSACHUSETTS.

REFRIGERANT.

Application filed December 19, 1922. Serial No. 607,795.

To all whom it may concern:

Be it known that I, JOSEPH MITCHELL CHANDLER, a citizen of the United States, residing at East Bridgewater, in the county 5 of Plymouth and State of Massachusetts, have invented new and useful Improvements in Refrigerants, of which the following is a specification.

The common refrigerating gases, such as 10 ammonia, sulphur dioxide and ethyl chloride, heretofore used for purposes of refrigeration, possess various objectionable features, such for example as their toxic properties, their corrosive effect on pipes or receptacles in which they are used, the heavy 15 pressures required for their condensation, and their action on lubricating oils.

I have discovered that methyl bromide (monobromomethane) possesses many 20 characteristics and properties which render its use, as a refrigerating gas, of great value in refrigeration, and the present invention consists of methyl bromide as a new or improved agent for use in a refrigerating machine. 25

Among the advantages secured by the use of this gas are the following. It has no corrosive action whatever on metals, and being neither acid nor alkali it has no tendency to 30 break down or deleteriously effect lubricating oils. Owing to the fact that its boiling point is 4.5° C., it requires only a low vacuum (or minus pressure) to boil in the expansion chamber of a refrigerating apparatus, and a low pressure in the condenser chamber for its liquefaction. Consequently 35 the possibility of sucking air on the reduced pressure side of the system and of leakage on the high pressure side are greatly minimized. Further methyl bromide is particularly adapted for use with certain types 40 of rotary compressor which have a high efficiency within the range of pressure required. Moreover, since only a low condenser pressure is required, there is a further 45 advantage of its use, from the standpoint of safety, in that the possibility of explosion is reduced, particularly when it is used in small automatic machines installed 50 in residences, shops, meat markets or other

places where the machines are not under the supervision and constant control of an engineer.

Again, there is no fire hazard incident to the use of methyl bromide as a refrigerating agent, or to its storage or shipment. Owing to the high density of the vapor, the volume of gas to be compressed is comparatively small, with a resultant high efficiency in refrigeration. 55

The toxic action is slight, but the odor, though pleasant, is readily detected, and thus any leakage is readily noted. 60

In addition to these advantages, others may be pointed out,—namely, the stability of 65 the gas in that it is not broken down even when subjected to comparatively high temperatures, and the practical impossibility of its generating permanent gases, due to its high critical temperature (194° C.). Moreover 70 it is unnecessary to use any particular precautions to remove air from the refrigerating apparatus, when methyl bromide is to be used therein.

On the accompanying drawing, I have 75 illustrated conventionally an apparatus for carrying out a process of refrigeration in which methyl bromide constitutes the refrigerating agent. The gas is compressed by the compressor 1 (which may be of the 80 rotary type), and passes through the condenser 2 to the pressure-reducing valve or other pressure-reducing device 3, thence to the expansion chamber 4, and finally returns to the compressor, thus completing 85 the cycle. The variation in pressure in the condenser and the expansion chamber is relatively small, and the pressure on the condenser side of the compressor is relatively low. 90

What I claim is:

The use, as a refrigerant capable of being alternately compressed and liquefied and then expanded and gasified, of that organic substance known as methyl bromide without 95 admixture with other agents.

In testimony whereof I have affixed my signature.

JOSEPH MITCHELL CHANDLER.
